UNITED STATES PATENT OFFICE.

WILLIAM B. HOPWOOD, OF BEACON FALLS, CONNECTICUT, ASSIGNOR TO THE BEACON FALLS RUBBER SHOE COMPANY, OF BEACON FALLS, CONNECTICUT, A CORPORATION OF MASSACHUSETTS.

DESIGN FOR A COMBINED SHOE SOLE AND HEEL.

Application filed November 18, 1927. Serial No. 24,197. Term of patent 14 years.

To all whom it may concern:

Be it known that I, WILLIAM B. HOPWOOD, a citizen of the United States, residing at Beacon Falls, county of New Haven, and State of Connecticut, have invented a new, original, and ornamental Design for a Combined Shoe Sole and Heel, of which the following is a specification, reference being had to the accompanying drawing, forming part thereof, wherein—

Figure is a plan view of the combined

shoe sole and heel looking at the tread surface; and

Figure 2 is a longitudinal section of Figure 1.

I claim:

The ornamental design for a combined shoe sole and heel as shown.

Signed at Beacon Falls, county of New Haven, State of Connecticut, this 15th day of November, 1927.

WILLIAM B. HOPWOOD.
